UNITED STATES PATENT OFFICE.

MARGARET BLANCHE JOHNSON, OF ALABAMA CITY, ALABAMA.

DESIGN FOR A BELT AND SKIRT-SUPPORT.

No. 37,595.

Specification for Design.

Patented Oct. 24, 1905.

Application filed August 10, 1905. Serial No. 273,682. Term of patent 7 years.

To all whom it may concern:

Be it known that I, MARGARET BLANCHE JOHNSON, a citizen of the United States, residing at Alabama City, in the county of Etowah and State of Alabama, have invented a new, original, and ornamental Design for a Belt and Skirt-Support, of which the following is a specification, reference being had to the accompanying drawing, forming a part thereof.

In the drawing accompanying the specification and made a part thereof the figure is a perspective view of a belt and skirt-support, showing my design.

I claim—

The ornamental design for a belt and skirt-support as shown.

MARGARET BLANCHE JOHNSON.
